Primary Examiner — Jennifer L Watkins(57) **CLAIM**

The ornamental design for a shoulder abduction arm support as shown and described.

DESCRIPTION

FIG. 1 is a top front side perspective view of a shoulder abduction arm support showing my new design;

FIG. 2 is a top front side perspective view of the shoulder abduction arm support with a cover flap in an alternate position;

FIG. 3 is a top view of the shoulder abduction arm support; FIG. 4 is a front view of the shoulder abduction arm support; FIG. 5 is a rear view of the shoulder abduction arm support; FIG. 6 is a bottom view of the shoulder abduction arm support;

FIG. 7 is a left side view of the shoulder abduction arm support;

FIG. 8 is a right side view of the shoulder abduction arm support; and,

FIG. 9 is a cross-sectional view of the shoulder abduction arm support taken along line 9-9 of FIG. 3.

1 Claim, 4 Drawing Sheets(56)
